(57) **CLAIM**

The ornamental design for a stair stringer connector as shown and described.

DESCRIPTION

FIG. 1 is a right side view of a stair stringer connector;
FIG. 2 is a left side view thereof;
FIG. 3 is a front view thereof;
FIG. 4 is a rear view thereof;
FIG. 5 is a top view thereof;
FIG. 6 is a bottom view thereof;
FIG. 7 is a section view thereof taken along line 7-7 of FIG. 5;

FIG. 8 is a right perspective view thereof;

FIG. 9 is a bottom perspective view thereof; and,
FIG. 10 is a perspective view thereof, showing the environment.

The broken lines in FIG. 10 are to depict the environmental structure and form no part of the design.
